(57) **CLAIM**

The ornamental design for a novel bird deterring effigy (eagle), as shown and described.

DESCRIPTION

FIG. 1 is an upper front right perspective view of the bird deterring effigy (eagle).

FIG. 2 is an upper front left perspective view of the bird deterring effigy (eagle) of FIG. 1

FIG. 3 is a lower front right perspective view of the bird deterring effigy (eagle) of FIG. 1

FIG. 4 is a lower front left perspective view of the bird deterring effigy (eagle) of FIG. 1.

FIG. 5 is an upper rear right perspective view of the bird deterring effigy (eagle) of FIG. 1

FIG. 6 is a lower rear right perspective view of the bird deterring effigy (eagle) of FIG. 1.

FIG. 7 is a front view of the bird deterring effigy (eagle) of FIG. 1.

FIG. 8 is a rear view of the bird deterring effigy (eagle) of FIG. 1.

FIG. 9 is a left side view of the bird deterring effigy (eagle) of FIG. 1.

FIG. 10 is a right side view of the bird deterring effigy (eagle) of FIG. 1.

FIG. 11 is a top view of the bird deterring effigy (eagle) of FIG. 1; and,

FIG. 12 is a bottom view of the bird deterring effigy (eagle) of FIG. 1.

1 Claim, 12 Drawing Sheets
